O. C. CRANDALL.
COMBINED SAND AND GRAVEL SCREEN.
APPLICATION FILED FEB. 3, 1920.

1,424,451.

Patented Aug. 1, 1922.

UNITED STATES PATENT OFFICE.

ORLANDO C. CRANDALL, OF STANWOOD, MICHIGAN.

COMBINED SAND AND GRAVEL SCREEN.

1,424,451.

Specification of Letters Patent. Patented Aug. 1, 1922.

Application filed February 3, 1920. Serial No. 355,936.

To all whom it may concern:

Be it known that I, ORLANDO C. CRANDALL, citizen of the United States, residing at Stanwood, in the county of Mecosta and 5 State of Michigan, have invented certain new and useful Improvements in Combined Sand and Gravel Screens, of which the following is a specification.

This invention relates to a combined stone 10 and sand screen and has as its principal object to provide a device of this character, which may be employed for screening sand or for screening gravel if the sand screen is covered.

15 A further object of the invention is to provide a device employing a frame having at one end a reticulate sand screen and at its opposite end a gravel grating, the frame being supported in an inclined position so 20 that in the use of the device, sand may be thrown toward the upper end of the frame to flow down over the sand screen while, by covering the sand screen, gravel may also be tossed toward the upper end of the frame 25 to roll down over the gravel grating.

And the invention has as a still further object to provide a device wherein the inclination of the screen frame may be readily varied or adjusted.

30 Other and incidental objects will appear hereinafter.

In the drawings—

Figure 1 is a perspective view showing my improved screen in position upon a conventional type of gravel box, the latter being shown in dotted lines.

Figure 2 is a longitudinal sectional view taken medially through the device, and

40 Figure 3 is a fragmentary transverse section taken through the cross bar of the gravel grating of the device.

In carrying the invention into effect, I employ an oblong screen frame having parallel side bars 10 connected by parallel end 45 bars which have been indicated at 11 and 12 respectively. The upper end bar is arranged with its width disposed vertically, while the lower end bar is arranged with its width disposed horizontally, this latter end bar being secured to the lower edges of the side bars. Extending between the side bars in spaced 50 relation to the upper end bar is a cross bar 13 lying parallel to the bar 11, and midway between the bars 12 and 13 is another cross bar 14 lying parallel to the bar 13. The several bars of the frame may be secured to- 55

gether in any approved manner and in this connection it will be observed that the bars 12, 13 and 14 are all lying flat and mortised into the lower edges of the side bars so as 60 to lie flush with the bottom edge of the end bar 11. A reticulate sand screen is suspended between the bars 11 and 13 and the side bars 10. This screen may be formed of any approved material and, bracing the 65 screen, are spaced brace rods 16 extending longitudinally of the frame between the bars 11 and 13. These brace rods may be connected at their ends to the cross bars in any approved manner and are designed to prevent 70 sagging of the intermediate portion of the screen. Seated upon the upper edges of the side bars 10 and the upper end bar 11 are side boards 17 extending about three of the sides of the screen 15 and providing, in 75 effect, a hopper therefor, the longitudinal side walls terminating at their lower ends in a plane with the lower edge of the cross bar 13. Secured at one edge of this cross bar is a rearwardly inclined sand apron 18 80 of a width corresponding to the width of the frame and fastened at its ends to the side bars 10.

Extending longitudinally between the bars 12 and 13 are transversely spaced parallel grating rods 19 forming a gravel grating in continuation of the screen 15 at the lower end portion of the frame. These rods are supported at their intermediate portions by the cross bar 14, and the bars 12 and 13 90 are provided in their upper faces with alined sockets, while the bar 14 has in its upper face grooves each alining with the corresponding sockets. The rods 19 are each engaged at their end portions in these 95 sockets, while the intermediate portion of each of said rods is received within the alining groove of the bar 14. The rods will thus be securely held against lateral movement with respect to each other and engaged through the end portions of the rods 100 as well as through the intermediate portions thereof are suitable fastening devices firmly securing the rods to the bars.

Fixed to the lower end portions of the side 105 bars 10 of the frame are short legs 20 extending from the bars at substantially right angles and pivoted to the upper end portions of said side bars are long legs 21 for supporting the frame. Adjacent their lower 110 ends, the legs 21 carry brackets 22 adjustable longitudinally of the legs and project-

ing rearwardly therefrom. As will be readily understood, the legs 20 and 21 are adapted to support the screen frame in inclined position, the legs 21 being swingingly adjustable for varying the inclination of the frame. However, in the drawings, I have shown the device in connection with a conventional type of gravel box 23, in order to bring out the manner in which the device 5 may be used in connection with such a box. As shown, the short legs 20 of the frame are placed against the inner side of one side wall of the box so that the lower end portion of the frame projects over said side wall. This done, the brackets 22 on the legs 21 are placed over the upper edge of the other side wall of the box so that the lower end portions of the legs 21 project at the outer side of this latter side wall. Thus the 10 legs will support the screen upon the box, and, as will be readily understood, the brackets may be adjustably positioned along the legs 21 for varying the inclination of the screen. Sand may then be thrown upon the 15 screen 15, when the screen will serve to separate stones and gravel from the sand, the latter flowing through the screen onto the apron 18 and directed thereby to one side of the gravel box and the gravel rolling 20 downwardly over the screen to fall through the gravel grating into the box, the stones falling over the lower end of the frame. For screening gravel, the screen 15 may be 25 suitably covered. This done, gravel may 30 then be thrown upon the cover to roll down over the gravel grating, the gravel falling 35

through the grating into the gravel box and any stone in the gravel being separated therefrom to be directed by the grating to the forward side of the box. 40

Pivoted upon the lower end portions of the side bars 10 is a stop member 24 normally projecting beyond the lower end of the screen and designed to prevent stones, rolling from the gravel grating, to strike a 45 workman standing adjacent the screen. As shown in Figure 2, the stop member 24 may be folded upwardly to lie between the side bars. It will accordingly be seen that I provide a device which may be readily employed for screening either sand or gravel and, when used in connection with a gravel box, gravel will be discharged into the box, 50 while sand will be discharged at one side and stone at the other side of the box. 55

Having thus described the invention, what is claimed as new is:

A screening device comprising a frame having a screening surface, stationary legs at the lower end of the frame for supporting 60 the same, legs pivoted to the upper portion of the frame at the opposite sides thereof and swingingly adjustable with relation thereto, and support clamping members longitudinally slidably adjustable upon the 65 lower ends of said last-mentioned legs, and hook-engaging members carried by said support clamping members and projecting at an angle to the respective legs.

In testimony whereof I affix my signature. 70

ORLANDO C. CRANDALL. [L. s.]
